United States Patent Office

Des. 205,958

Patented Oct. 11, 1966

205,958

POCKET WASHBOARD

Inga L. Nordby, 12251 Rutherford, Detroit, Mich.

Filed Feb. 17, 1966, Ser. No. 1,100

Term of patent 14 years

(Cl. D49—1)

FIG. 1

FIG. 2

FIG. 3

FIG. 1 is a front elevational view of a pocket washboard, showing my new design.

FIG. 2 is a section taken on line 2—2 of FIG. 1.

FIG. 3 is a bottom plan view thereof.

I claim:

The ornamental design for a pocket washboard, substantially as shown.
